UNITED STATES PATENT OFFICE.

HENRY E. SPAUNHORST, OF ST. LOUIS, MISSOURI.

COMBINED DRAWER GUIDE AND STOP.

SPECIFICATION forming part of Letters Patent No. 461,375, dated October 13, 1891.

Application filed June 12, 1891. Serial No. 396,017. (No model.)

To all whom it may concern:

Be it known that I, HENRY E. SPAUNHORST, of the city of St. Louis, and State of Missouri, have invented certain new and useful 5 Improvements in a Combined Drawer Guide and Stop, of which the following is a full, clear, and exact description, reference being had to the accompanying drawings, forming a part hereof.

10 My invention relates to improvements in a combined drawer guide and stop; and it consists in the novel arrangement and combination of parts, as will be more fully hereinafter described, and designated in the claims. 15 In the drawings, Figure 1 is a vertical cross-section of a desk having my invention applied thereto. Fig. 2 is a perspective view of the guide, having the slide located therein. Fig. 3 is a vertical longitudinal section of the 20 same. Fig. 4 is a perspective view of the slide detached, and Fig. 5 is a side elevation of a spring which I employ in connecting the drawer to the slide.

Referring to the drawings by numerals, 1 25 represents a desk of ordinary construction, and 2 2 are two longitudinal beams extending the entire length of the desk and attached to the same in the usual manner.

3 represents the guide, which is formed of 30 a single piece of metal, the edges of which are bent upwardly and inwardly, which, when thus formed, leaves a space 4, the object of which will be hereinafter stated. One end of the guide leading from the bottom 35 thereof is bent at right angles thereto and extends a little beyond the sides of said guide and is provided with suitable apertures 5, by which means the guide may be fastened to one of the longitudinal beams secured within 40 the desk 1. To effect a permanent and fixed position of the guide, the base of the same at the opposite end thereof, or the upwardly-turned portion, is provided with a second set of apertures, through which nails or screws 45 may be inserted for fastening to the other beams 2, located within the desk, as better illustrated in Fig. 1.

6 represents a lip formed integral with the 50 guide and bent at right angles to the base thereof, and is formed by slitting the same, as shown in Fig. 2, thereby leaving a square

opening 7 in said base portion of the guide. The object of the lip 6 is to form a stop for the slide 8 when the drawer 9 is opened, thereby preventing the same from being withdrawn entirely from the desk. Said slide 8 consists of a flat piece of metal of sufficient thickness to fit snugly and yet easily movable within the guide, as will be fully observed, thereby dispensing with as much lost motion as possible in a transverse direction to said guide.

10 represents an elongated opening formed in the plate or slide 8, thereby forming two parallel arms 11, which pass on both sides of 65 the lip 6 when the said slide is drawn outward.

12 represents a square block of metal fastened in any desirable manner to the slide 8, by which means and other devices the said 70 slide is connected to the drawer.

13 represents a spring made of a flat piece of metal, one end of which is secured to the under surface or bottom of the drawer 9, and the opposite end thereof passes through an 75 opening 14, formed in said bottom of the drawer, whereby it is in easy reach and when desired can be operated. At or near the medium portion of the spring 13 is formed therein a raised angular portion 15, corresponding to 80 the block 12, carried by the slide 8, and which is adapted to fit over the same when the device is in functional operation.

It will be observed from the foregoing description that when the device is in its normal 85 position, as shown in Fig. 1, the drawer is connected to the slide 8 by means of a spring 13, thereby forming a stop and also a guide for the drawer.

Should it become necessary to withdraw the 90 drawer entirely from the desk the said drawer may be partially opened in order to allow the insertion of the hand to manipulate the spring 13. By so doing the slide will be released by the spring 13 by the act of raising the said 95 spring, and thereby allow the drawer to be withdrawn.

When it is desired to again locate the 100 drawer in its normal position on or in connection with the slide, the drawer is merely inserted in the desk in the usual manner, and by entirely closing the same the slide will

pass into its proper position under the spring 13 and lock the same automatically.

From the construction of my invention, as will be fully seen, the usual guides employed for the drawers may be dispensed with and also the support for the same, if found desirable.

Having fully described my invention, what I claim is—

- 10 1. In a combined drawer guide and stop, a guide 3, an upturned portion at one end thereof and a flattened portion at the opposite end for securing said guide in position, a stop 6 in the guide, a slide moving in the guide, 15 provided with a central opening 10 for the reception of said stop, a block on said slide, and a device secured to the drawer adapted to engage said block, substantially as described.
- 20 2. In a combined drawer guide and stop, a guide 3, formed of a single piece of metal, a

slide 8, adapted to move therein, and a block 12, secured to said slide, in combination with a spring carried by the drawer, adapted to engage block 12 for connecting and disconnecting said drawer from the slide, substantially as described.

3. In a combined drawer guide and stop, the combination of the guide 3, stop 6, formed integrally therewith, the slide 8, adapted to move within said guide and having an elongated opening 10 formed therein, a block, such as 12, carried by the said slide, and a spring 13, carried by the drawer and adapted to engage with said block, substantially as set forth. 35

In testimony whereof I affix my signature in presence of two witnesses.

HENRY E. SPAUNHORST.
